UNITED STATES PATENT OFFICE.

JOHN RUTSON VAN TASSEL, OF GENEVA, NEW YORK, ASSIGNOR OF ONE-HALF TO STANDARD OPTICAL COMPANY, OF GENEVA, NEW YORK, A CORPORATION, AND ONE-HALF TO GUSTAV A. BADER, OF ROCHESTER, NEW YORK.

EYEGLASS-MOUNTING.

1,192,714.

Specification of Letters Patent. Patented July 25, 1916.

Application filed August 18, 1915. Serial No. 46,113.

To all whom it may concern:

Be it known that I, JOHN RUTSON VAN TASSEL, a citizen of the United States, and resident of Geneva, in the county of Ontario 5 and State of New York, have invented certain new and useful Improvements in Eye-glass-Mountings, of which the following is a specification.

This invention relates to eyeglass-mountings of the type in which the nose-clamps or guards are carried by spring-controlled levers, which are pivoted at the ends of a rigid bridge and controlled by finger-pieces at the front of the mounting.

One object of the invention is to provide, in a novel and simple manner, for the support of the springs by which the nose-clamp levers are controlled.

Another object of the invention is to provide stops to limit the swinging movements of the levers about their pivots.

A third object of the invention is to provide smooth flat bearing-surfaces for the nose-clamp levers, adjacent the pivots on 25 which they are mounted.

To the foregoing ends I employ, in connection with the bridge, the nose-clamp lever and the pivot by which the lever and the bridge are connected, a sheet-metal member 30 which is interposed between the lever and the bridge, thus providing a bearing-surface for the lever, and this member is provided with an arm adapted to serve as a support for the spring by which the lever is controlled, or with lugs adapted to act as stops to limit the swinging movements of the lever, or with both of these features, while it is also so formed as to prevent it from turning, on the bridge, about the pivot by which it is 40 secured in place.

In the accompanying drawings: Figure 1 is a plan-view of a part of an eyeglass-mounting embodying the present invention, on a greatly enlarged scale; Fig. 2 is a rear-elevation of the same part; Fig. 3 is a right-hand elevation of the same part, with the bridge shown in section on the line 3-3 of Fig. 2; and Fig. 4 is a perspective view of the combined bearing, spring-supporting 45 and stop-member in which the present invention particularly resides.

The invention is illustrated in an eyeglass-mounting in which each lens 5 is fixed in the usual lens-clip 6, this clip being fixed

to one end of the rigid bridge 7 in the usual 55 manner. The bridge is perforated vertically to receive the pivot-stud 8, which is screwed or otherwise fastened in the bridge, and on this stud is mounted the nose-clamp lever 9, provided with the usual finger-piece 60 10 for operating it.

The nose-clamp lever does not directly engage the bridge 7, but has a bearing upon the upper surface of a sheet-metal member 11, which lies upon the upper surface of the 65 bridge and is perforated to receive the pivot-stud 8, being thereby fixed in position on the bridge. This member 11 has a straight edge 12 which engages the lens-clip, as shown particularly in Fig. 1, so as to prevent rotation 70 of the member on the bridge, and such rotation is further prevented by a lug 13, bent downwardly from the member and engaging the forward surface of the bridge.

The member 11 performs several useful 75 functions. In the first place, it provides a flat and smooth bearing-surface for the nose-clamp lever. In the manufacture of a mounting of the type in question the operations by which the bridge is shaped, perforated, and attached to the lens-clip are 80 such as tend to leave the upper surface of the bridge more or less uneven and rough, and difficulty and expense are encountered in securing a smooth bearing-surface at this 85 point. The member 11 being stamped from smooth sheet-metal, affords such a bearing-surface in a convenient and inexpensive manner, and avoids the necessity of great care in forming and finishing the upper 90 surface of the bridge. In the second place, the member 11 serves as a convenient means for providing a support for the spring by which the nose-clamp lever is controlled.

To this end an arm 14 is formed integral 95 with the member 11, this arm being bent downwardly at the inner edge of the member, and serving as a support for the coiled part of the spring 15, this spring having ends 16 and 17 which engage, respectively, 100 the lever and the lens-clip. To secure the spring in place on the arm 14 the lower extremity 18 of the arm is bent inwardly, as shown in Figs. 3 and 4. In the third place, member 11 provides conveniently for the 105 provision of stops to limit the swinging movements of the nose-clamp lever. For this purpose lugs 19 and 20 are bent upwardly

at the inner corners of the member 11, in position to engage the edge of the nose-clamp lever and limit, respectively, its outward and inward swinging movements.

5 I claim:—

1. In an eyeglass-mounting, the combination, with a bridge, a nose-clamp lever, and a stud, upon which the lever is pivoted, fixed in the bridge, of a bearing-plate interposed 10 between the bridge and the lever and having a lug arranged to engage the lever to limit the swinging movement thereof.

2. In an eyeglass-mounting, the combination, with a bridge, a nose-clamp lever, and 15 a stud, upon which the lever is pivoted, fixed in the bridge, of a bearing-plate interposed between the bridge and the lever and having an arm, which extends substantially parallel

with the pivot-stud and alongside the bridge, for the support of a coiled spring, 20 and two stop-lugs, which extend in the opposite direction from the body of the plate, to engage the lever and limit the swinging movement thereof.

3. In an eyeglass-mounting, the combination, with a bridge, a nose-clamp lever, and a stud, upon which the lever is pivoted, fixed in the bridge, of a bearing-plate interposed between the bridge and the lever and having an arm, extending substantially parallel 30 with the pivot-stud, for the support of a coiled spring, and a lug arranged to engage the lever to limit the swinging movement thereof.

JOHN RUTSON VAN TASSEL.
